WALL HOOK

Edward H. Tate, Frank E. B. Tate, and Christopher Tate, Malden, Mass., assignors to E. H. Tate Company, Boston, Mass., a corporation of Massachusetts

Application December 24, 1935, Serial No. 55,998

3 Claims. (Cl. 206—79)

This invention relates to an improved wall hook of the type comprising a strip of metal bent to suitable shape and provided with a pin or nail extending therethrough to be driven into a wall so as to support the hook.

It is an object of the invention to provide improvements in the hook which will facilitate manufacture thereof, will provide for suitable frictional engagement between the pin and the metal strip so as to maintain these two members frictionally assembled, and will facilitate the mounting of the hooks on display cards.

In shaping the metal strips into hook form, automatic machines are customarily employed. While these machines act with a considerable degree of uniformity, the product is subject to slight variations due to variation in the quality or thickness of the metal stock supplied or to other causes. It is desirable that the pin or nail, which is employed with the bent strip of metal, be held in place by frictional engagement with the metal strip, this engagement being such as to hold the pin in assembled relation with the strip but to permit its removal from the strip if desired.

According to the invention, the lower portion of the metal strip is bent into hook form, the upper end portion of the strip being formed into a closed loop. A tongue is struck up from the looped portion of the strip in such a manner that the tongue engages the side of the pin which is thrust through a pair of opposed holes in the loop. The tongue bears frictionally against the pin with a pressure which may vary in different hooks owing to slight variations in the shape of the loop, as formed in the machine, as may vary the position of the pin relative to the portion of the loop from which the tongue is struck. The tongue is adapted to yield sufficiently to avoid excessive differences in frictional drag on the pin from such variations in the position of the pin. This tongue has an additional function of facilitating the assembling of wall hooks on a display card as hereinafter described. In order to maintain the tongue in correct position for frictional engagement with the pin, the extreme end of the upper portion of the strip, which is bent back into contact with the rear portion to form the loop, is preferably supported by suitable means such as a tongue struck out from the rear portion of the strip so as to engage under the end of the strip and support the loop against distortion when the pin is being driven into a wall.

For a more complete understanding of the invention, reference may be had to the description

which follows and to an illustration of an embodiment thereof in the drawing of which

Figure 1 is a perspective view of a metal strip bent into shape and ready to receive a pin.

Figure 2 is an elevation of a display card having a complete wall hook attached thereto, the wall hook being shown in section.

Figure 3 is a fragmentary perspective view of a card having an ear adapted to be attached to a wall hook.

Figure 4 is a perspective view of a card showing a plurality of ears and a wall hook attached to one of them.

As indicated in Figure 1, a wall hook embodying the invention may be made by forming a pair of holes in a strip of metal, striking up therefrom a pair of tongues, and bending the strip to desired shape. As shown, a portion 10 of the strip of metal is left unbent to serve as the back of the completed wall hook. The lower portion of the strip is bent up to form a suitable hook 11. The upper portion of the strip is bent forward as at 12, and then diagonally rearward and downward as at 13, so that the extreme end 14 engages the forward face of the back portion 10 so as to complete a closed loop 15. At opposite points in this loop a pair of holes 20 and 21 are formed to receive a suitable pin or nail 25. These holes are preferably so disposed as to hold the pin 25 substantially parallel to the diagonal portion 13 of the loop. In order to support the loop against distortion when the pin 25 is driven into a wall, the lower end 14 preferably engages behind a tongue 30 which is struck out from the back portion 10 of the hook. A second tongue 31 is struck up from the portion 13 of the strip so as to project into the loop and to bear frictionally against the side of the pin 25. While the tongue 31 may have considerable stiffness owing to the thickness and character of the metal, yet it is capable of yielding sufficiently to prevent excessive friction against the pin 25 when variations occur in the shape of the loop as the hook comes from the forming machine or in the thickness of the pin 25. The tongue 30, in supporting the loop against distortion, helps to maintain the tongue 31 in suitable relation to the pin 25 in spite of severe stresses on the loop which may arise from hammer blows when the pin 25 is being driven into a wall.

For convenience in handling and selling wall hooks of this kind, they may be mounted on suitable display cards such as the card 40 illustrated in Figure 4. From the body of the card a suitable number of ears 42 are struck up, each

ear having a slit 44 cut therein perpendicular to the line of bend 45. The slits 44 are adapted to receive the tongues 31 of the hooks, the tongues projecting through the slots in the manner indicated in Figure 2. In assembling hooks and cards, the hook is placed edgewise against the face of the card in such a manner that an ear 42 projects through the loop 15. The tongue 31 is then pushed through the slit 44. The pin 25 is then thrust through the holes 20 and 21, the side of the pin thus coming into frictional engagement with the end of the tongue 31 so that the tongue cannot then be withdrawn from the slit 44.

15 Additional ears or tabs 50 may also be struck up from the card 40 to engage the lower portions of the hooks 40 and to hold the hooks more firmly on the card, especially hooks of the larger sizes. As shown, the tabs 50 are preferably located within the hook portion 11, between the parallel wall portions thereof. The tabs 50 are preferably of such a width as to engage tightly between the parallel wall portions of the hooks. This frictional engagement helps to hold the hooks against the cards as well as to prevent swinging about the tabs 42.

It is evident that various modifications and changes may be made in the invention herein illustrated and described without departing from the spirit or scope thereof as defined by the following claims.

We claim:

1. In combination, a wall hook comprising a strip of metal having an end portion bent into hook form and the other end portion bent to form a closed loop, a pin projecting through said

strip at two points on opposite sides of said loop, a display card having an ear struck up therefrom, said strip being disposed with one edge against a face of said card and with said ear within said loop parallel to said pin, and a tongue 5 struck up from the looped portion of said strip, said tongue projecting through said ear and bearing frictionally against said pin.

2. In combination, a wall hook comprising a strip of metal having its upper end portion bent 10 to form a closed loop, a pin projecting through said strip at two points on opposite sides of said loop, a card having an ear struck up therefrom to project into said loop and to extend along one side of said pin, said strip having a tongue 15 struck up from the looped portion thereof to project through said ear and to engage the side of said pin frictionally, the lower end of said strip being bent into hook form, and a second ear struck up from said card to engage frictionally in said hook.

3. In combination with a display card, a wall hook comprising a strip of metal having its lower portion bent into hook form and having its upper portion attached to the card so as to hold the 25 wall hook edgewise against the card, and means to prevent side swing of said lower hooked portion of the wall hook on said card, said means comprising a tab upstanding from said card and extending transversely within the hook of said 30 lower portion from one opposing face to the other, the side edges of said tab being substantially in contact with said opposing faces respectively.
